UNITED STATES PATENT OFFICE

99,324

DESIGN FOR A PLAYING BOARD FOR CHILDREN'S GAME

William J. Burke, Brazil, Ind.

Application November 30, 1934, Serial No. 54,200

Term of patent 14 years

To all whom it may concern:

Be it known that I, William J. Burke, a citizen of the United States, residing at Brazil, in the county of Clay and State of Indiana, have invented a new, original, and ornamental Design for a Playing Board for Children's Game, of which the following is a specification, reference being had to the accompanying drawing, forming part thereof.

The figure is a plan view of a playing board for children's game, showing my new design.

The parts of the drawing shown in solid lines represent the dominant features of my design.

I claim:

The ornamental design for a playing board for children's game, as shown and described.

WILLIAM J. BURKE.
